ATTORNEY

UNITED STATES PATENT OFFICE.

TIMOTHY M. SHEA, OF KNOXVILLE, TENNESSEE.

FOLDING SQUARE.

1,285,811.

Specification of Letters Patent.

Patented Nov. 26, 1918.

Application filed May 25, 1918. Serial No. 236,570.

To all whom it may concern:

Be it known that I, TIMOTHY MARTIN SHEA, a citizen of the United States, residing at Knoxville, in the county of Knox and State of Tennessee, have invented certain new and useful Improvements in Folding Squares, of which the following is a specification.

This invention relates to a square for the use of carpenters, masons and other mechanics for measuring and truing their work and has for its particular object to provide a square, which is usually made with blades from one to two feet in length and therefore difficult to pack in a tool chest and inconvenient to carry, with a simple joint for connecting the blades together by means of which they may be folded parallel with each other for easy transportation and which may be quickly opened into their normal right angular position and rigidly fastened together and maintained accurately at an angle of ninety degrees to each other. The connection between the blades which permit them to fold is such that when in folded position or when opened for use, the blades are interlocked in such manner as to prevent movement of the blades, but of such simple construction that the blades may be quickly and easily changed from open to closed position or vice versa, without trouble and in a relatively short space of time.

With these objects in view, together with others which will appear as the description proceeds, the invention resides in the novel formation, combination and arrangement of parts, all as will be described more fully hereinafter, particularly pointed out in the claims, and illustrated in the accompanying drawings, in which:

Figure 1 is a face view of the improved square in position for use.

Fig. 2 is an enlarged detail view of the folding connection between the blades of the square as seen from the side opposite that shown in Fig. 1.

Fig. 3 is a face view of the square showing the blades folded.

Fig. 4 is a cross sectional view on the line 4—4 of Fig. 2.

Fig. 5 is a similar view on the line 5—5 of Fig. 3.

Fig. 6 is a detail perspective view of the joint between the blades of the square, the elements forming the joint being shown separated.

Fig. 7 is a similar view of the blade joint showing a modified construction.

In the drawings, 10 indicates the longer blade or body of the square and 11 the shorter blade or tongue. These blades are each made of a strip of steel of the desired length, width and thickness and provided on opposite sides and both edges with the usual scale markings as shown. Through one end of the body blade 10 is a perforation 12 for the passage therethrough of a pivot bolt or screw 13. The perforation 12 is positioned in the body in the longitudinal center thereof at a distance from the end of the blade equal to one half the width of the tongue 11 so that when the parts of the square are in working position as in Fig. 1 the end of the body and the outer edge of the tongue will lie in the same plane. 75

Projecting from one face of the body 10 on opposite sides of the perforation 12 near the working edges of the body are two studs 14 spaced equally distant from the perforation 12 and separated sufficiently to permit the tongue 11 to pass between them when the blades are folded, as clearly shown in Fig. 3.

The tongue blade 11 is also provided with a perforation 15 for the pivot bolt 13 near one end in the longitudinal center of said tongue and spaced from the end a distance equal to half the width of the body 10, whereby its end will lie in the plane of the outer edge of the body when the blades are 90 in working position. On opposite sides of the perforation 15 in the longitudinal center of the tongue 11 are two perforations 16 into which the studs 14 fit snugly and hold the tongue at a true angle of ninety degrees to 95 the body 10. A nut 17 threaded on the pivot bolt 13 holds the blades securely together in either folded or working position.

To fold the square when the blades are open, the nut 17 is loosened sufficiently to 100 permit withdrawal of the studs 14 from the perforations 16, whereupon the tongue may be swung parallel with the body and above the same and the nut again tightened upon the bolt, thereby securing the tongue flatwise against the blade and its edges between the studs 14, which prevent the tongue swinging beyond the edges of the body should the nut 17 become loosened on the bolt. It is only necessary when the blades are to be 110 opened to loosen the nut, swing the tongue in a position perpendicular to the body until

the perforations 16 aline with the stud 14 whereupon the studs are inserted in said perforations and the nut tightened.

5 A square constructed as described is convenient, useful and easily carried in a tool chest. The folding blades being connected by a simple joint that holds the blades in true position, permits quick change of position of the blade and has no disengageable 10 parts which may be lost or misplaced.

15 The foregoing description and the drawings have reference to what may be considered the preferred, or approved form of my invention. It is to be understood that I may 20 make such changes in construction and arrangement and combination of parts, materials, dimensions, et cetera, as may prove expedient and fall within the scope of the appended claims.

25 One form of this change of construction is shown in Fig. 7 wherein the connected end of each blade is cut away for one half its thickness to form a shoulder 18 against which the inner edge of the opposite blade is firmly seated, the two blades being connected together as in the preferred form by a bolt 13 and nut 17 passing through perforations 12 and 15 in the respective blades. By means of this construction the two blades 30 when connected are in the same plane and may be quickly turned into parallel relation for storage or carriage purposes, by loosening the bolt and nut connection and turning the two blades in line.

35 Having thus fully described my invention, what I claim as new and desire to secure by Letters Patent is:

1. A mechanic's square comprising a pair of blades separably pivoted together, studs 40 projecting from the face of one of said

blades and separated a distance equal to the width of the other blade to permit said other blade to lie between them when the blades are in parallel relation, said other blade having perforations to engage said studs and hold the blades rigidly and truly in working position.

2. A mechanic's square comprising a pair of separable blades pivotally connected together at one end and foldable one upon the other, a pair of studs projecting from the face of one of said blades on opposite sides of the pivotal connection and spaced apart a distance equal to the width of the other blade to permit said other blade to extend 50 between them when the blades are folded, perforations being formed in said other blade to engage said studs when the blades are in working position to hold them rigidly and truly in place, and a pivot bolt between 55 the blades permitting limited separation thereof.

3. A mechanic's square comprising a pair of separable blades of different widths pivotally connected together each at one end, 60 studs projecting from one face of the wider blade and disposed in a line transversely of said blade and adapted to engage longitudinally arranged perforations in the narrower blade to hold said blades perpendicular to each other and to lie against opposite edges of the narrower blade when said blades are arranged parallel, and a tightening screw forming the pivot of said blade.

In testimony whereof I affix my signature 75 in presence of two witnesses.

TIMOTHY M. SHEA.
